(76) Inventors: **Ebenezer Shove; Thomas Hunt**

*Ebenezer Shove and Thomas Howland
Letters Patent.*

The Article referred to in these Letters Patent and making part of the same containing a description in the words of the said Ebenezer Shove and Thomas Howland themselves of their improvement in tanning and manufacturing Hides with Leather.

This improvement consists in the process of working off the hair with greater facility and with more safety than in any other mode of sweating, and at the same time with less vibration and relaxation of the fibres of the Hides. For this purpose hang or suspend the Hides singly by one edge in a light place, that is fit prepared for the purpose, occasionally changing their edge for edge after a day or two. A small opening or vacancy should be left in each end of the place, that is fit, that the air may circulate to carry off the steam raised by air.

When there are indications of too much heat, care must be taken to drench the Hides with cold water. The manner of hanging or suspending the Hides as above mentioned prevents them from pressing upon each other and thereby the sweating process is consequently carried on more regularly and uniformly, and without the necessity of applying any heat, so that it may be denominated the cool sweating process.
